Patented July 19, 1960

188,436

FLUORESCENT LIGHTING FIXTURE

Ernst Budke and Robert J. Renaud, Pittsburgh, Pa., assignors to Sylvania Electric Products Inc., a corporation of Delaware

Filed Nov. 2, 1959, Ser. No. 58,155

Term of patent 14 years

(Cl. D48—23)

Fig. 1.

Fig. 2.

Fig. 3.

Fig. 4.

Fig. 5.

Fig. 6.

Figure 1 is a perspective view of a fluorescent lighting fixture showing our new design;

Figure 2 is a side elevation thereof, the opposite side being the same;

Figure 3 is a top plan view thereof;

Figure 4 is an enlarged end elevation thereof, the opposite end elevation being the same;

Figure 5 is a fragmentary bottom view thereof; and

Figure 6 is a fragmentary side elevation of the end portion of the fixture shown on an enlarged scale with portions shown broken away to better illustrate the configurational details.

The fixture is shown broken away in Figures 2 and 3 for convenience of illustration only.

We claim:

The ornamental design for a fluorescent lighting fixture, as shown and described.
